[57] CLAIM

The ornamental design for an adjunct answering machine, as shown and described.

DESCRIPTION

FIG. 1 is a top, front and right side perspective view of an adjunct answering machine showing our new design; FIG. 2 is a front elevational view thereof; FIG. 3 is a rear elevational view thereof; FIG. 4 is a right side elevational view, the left side elevational view being a mirror image thereof; FIG. 5 is a top plan view thereof; and FIG. 6 is a bottom plan view thereof.

*FIG. 1**FIG. 2**FIG. 3**FIG. 4**FIG. 5**FIG. 6*
